CLAIM

The ornamental design for a self-propelled guide robot and/or replica thereof, as shown and described.

DESCRIPTION

FIG. 1 is a front view of a self-propelled guide robot and/or replica thereof;

FIG. 2 is a rear view thereof;

FIG. 3 is a plan view thereof;

FIG. 4 is a bottom view thereof;

FIG. 5 is a left side view thereof;

FIG. 6 is a front perspective view thereof as seen from the left side; and,

FIG. 7 is a rear perspective view thereof as seen from the right side.

The broken lines shown in the drawings illustrate portions of the self-propelled guide robot and/or replica thereof that form no part of the claimed design.

1 Claim, 3 Drawing Sheets
